UNITED STATES PATENT OFFICE.

FREDERICK J. QUINCY, OF BROOKLYN, NEW YORK, ASSIGNOR TO ENGLANDER SPRING BED COMPANY, OF BROOKLYN, NEW YORK, A CORPORATION OF NEW YORK.

COUCH AND COUCH-BED.

1,089,723.

Specification of Letters Patent.

Patented Mar. 10, 1914.

Application filed April 18, 1912. Serial No. 691,593.

To all whom it may concern:

Be it known that I, FREDERICK J. QUINCY, a citizen of the United States, residing at Brooklyn, in the county of Kings and State 5 of New York, have invented certain new and useful Improvements in Couches and Couch-Beds, of which the following is a specification.

This invention relates to couches and 10 couch beds, the object of the invention being to provide an improved structure of this class in which the legs may be readily folded so that the couch may occupy a small space when not in use or for shipment and in 15 which the legs will be rigidly supported when the article is in use and prevented from slippage along the side bar when the couch is raised on its end.

One of the objects of the present invention 20 is the provision in connection with suitable supporting means of improved folding or swinging legs which may be readily folded into parallel relation with the spring and which in either of their folded or vertical 25 positions will be prevented from shifting lengthwise of their supporting means, usually in the form of a side-bar, and which improvement will also permit the folding legs to be locked in one of their positions.

With those forms of folding legs which 30 are swingingly supported by a side bar so that they may be folded into a horizontal position, and which, in order to fold them or to position them in an upright position, are 35 shiftable relatively to the side bar such legs, when the couch or divan has been lifted end- 40 wise or stood upon its end, have slipped or shifted downward on the side bar and, owing to the weight thereof, injury has resulted to 45 the person handling the structure. By means of the present improvement, however, owing to the manner in which the legs are connected with the side bar, they may be shifted to permit the swinging thereof but they cannot shift or drop along the side 50 bar when the structure is set upon its end.

In the drawings accompanying and forming 55 part of this specification, Figure 1 is a side elevation partly in section; Fig. 2 is a longitudinal sectional view of one of the leg couplings; Fig. 3 is a transverse section on the line 3—3 of Fig. 2, with a section of one of the side rails therein and illustrates the socket when moved into its horizontal position to carry the leg into its folded posi-

tion; Fig. 4 is a perspective view of one end of a side bar or rail; and Fig. 5 illustrates the improvement arranged to lock the leg in its upright position.

Similar characters of reference indicate 60 corresponding parts throughout the figures of the drawings.

For the purpose of illustration the present improvement is shown applied to a conventional divan including end angle bars 2 65 for supporting the spring 3. Connected to the end bars 2, at each end thereof, is a supporting bracket 4 secured, as at 5, to the depending webs 6 of the end bars 2. Each bracket includes a cylindrical socket 7 provided with an internal stop or lug 8. A pair of opposite sockets receive the ends of a side rail 9 provided with recesses 10 in the ends adapted to engage the lugs 8. By this simple means it will be obvious that when 70 the rails 9 are inserted into the sockets and engage the stops or lugs 8 the rails are coupled in the blocks and prevented from turning therein. The side rails are spaced below the spring along its side edges. The 75 rails 9 support foldable legs of improved construction, and as the legs are precisely alike a description of one will suffice for all.

Each of the foldable legs 11 comprises a sleeve 12 mounted for rotation on the side rail 9. This sleeve is provided with a socket 13 in which the end of the leg 11 is secured by a pin 14 or other suitable fastening means. Each of these sleeves 12 is provided with an L-shaped or "bayonet" slot 15 through one 80 side and with a radial slot 16 in the opposite side. Extending from one side of the sleeve 12, (see Figs. 1, 2 and 3), and partly covering the slot 16 is a hood 17, and formed within the sleeve, adjacent to the inner end of the slot 16, is a pocket or depression 18 with which the interior of the hood 17 communicates. The pocket 18 is somewhat longer than the longitudinal portion of the slot 15, as shown in Fig. 2. The opening 16 being located opposite the slot 15 provides 85 means for the insertion of a bolt 19, the opening being of sufficient width to receive the head 20 of the bolt. The rail 9 is provided with a transverse aperture 21 through which the bolt 19 is designed to be passed. By this construction, when the sleeve 12 is disposed over the rail 9, with the transverse aperture 21 thereof in alinement with the slot 16 and radial portion of the slot 15, the bolt 19 90

110

may be inserted therethrough with its head opposite the interior of the hood 17, and then when the sleeve is rotated upon the rail the head of the bolt will pass into the recess 18, while the threaded end of the bolt 5 will project through the aperture 15 in position to receive a wing nut 22. By this simple means the sleeve may be readily coupled in position to support the leg portion 11 in 10 vertical position with the bolt 19 in the bottom of the radial portion of the slot 16, as shown in Fig. 1, or by loosening the wing nut the sleeve, together with its leg, may be rotated one-fourth of a revolution on the 15 side rail to dispose the leg in a horizontal or parallel position relatively to the spring 3, and thus dispose the legs in folded position. When the legs are disposed in vertical position, the sleeve can be moved longitudinally 20 of the rail to move the longitudinal portion of the slot 15 over the bolt and thus lock the sleeve with the leg in vertical position, as will be obvious.

In Fig. 5 the sleeve 12 is provided with a 25 pair of L-shaped slots 30 and 31 opposite each other, and both at one side of the leg 13, and in this form of the improvement when the leg is in its perpendicular position the sleeve may be shifted lengthwise of the 30 side bar so that the longitudinal part 32 of the slots will receive the bolt and so lock the leg against swinging movement, while the radial portions 33 of the slots will permit the leg to be folded.

This improved device is simple in construction, can be inexpensively manufactured and strongly constructed, and the improved couch may be readily shipped in "knocked down" condition by releasing the 35 side bars or rails from the stops 8 at one end of the structure and withdrawing the rails 9.

It will be observed that in all of the forms shown in Figs. 1, 2 and 3, the radial slot 16 40 communicates with the pocket 18, which as hereinbefore stated is slightly longer than the portion 15 of the bayonet shaped slot, so that while the radial portion 16 and the pocket 18 form in a sense a bayonet shaped 45 slot yet they are of different form from the slot 15 and its radial portion. In the form of the structure shown in said Figs. 1, 2 and 3, it will be observed that the pocket 18 is just above the sleeve 13.

In the form shown in Fig. 5 in which the bayonet shaped slots are located to permit the leg to be locked in a vertical position, although the mere repositioning of these 50 slots will permit it to be locked in a horizontal position, it will be observed that both the bayonet shaped slots are to one side of the sleeve 13 in which form of the improvement the hood 17 is not necessary.

I claim as my invention:

1. In a structure of the class described

having side-bars, rotatable legs provided with sleeves mounted for rotation upon said bars each of said sleeves having a pair of radial slots at opposite points, a bolt located in position to work in said radial slots 70 and means engaging said bolt for clamping the sleeve upon the bar, whereby when the bolt is within said radial slots the movement of the sleeve lengthwise of the bar is prevented.

2. In a structure of the class described having side bars, rotatable legs provided with sleeves mounted for rotation upon said bars, each of said sleeves having a bayonet-shaped slot therein and at another side 80 thereof a radial slot, and a bolt carried by said bar and projecting into said slots.

3. In a structure of the class described having side-bars, rotatable legs provided with sleeves mounted for rotation upon said 85 bars each of said sleeves having a bayonet shaped slot therein, and a bolt carried by said bar and having a part projecting into said slot for securing the sleeve to the bar one portion of said slot permitting rotary 90 movement of the sleeve and another part thereof preventing such rotary movement and said bayonet shaped slot permitting only a limited movement of the sleeve lengthwise on the bar.

4. In a structure of the class described having side-bars, legs provided with sleeves rotatable on said side-bars each of said sleeves having a bayonet shaped slot effective to permit rotation and sliding movement on its side-bar, and also having a radial slot terminating in a pocket and a bolt carried by said side-bar and coöperating with said slots, whereby the leg may be rotated and slid to lock the same against 100 movement.

5. In a structure of the class described having side-bars, rotatable legs provided with sleeves rotatable on said side-bars each of said sleeves having a pair of radial slots 110 each terminating in a pair of lengthwise extending openings, and a bolt carried by said side-bar and coöperating with said openings and slots, whereby the leg may be rotated and slid to lock the same against 111 movement in a predetermined position.

6. In a structure of the class described having side-bars, rotatable legs provided with sleeves rotatable on said side-bars, each of said sleeves having a bayonet-shaped slot 120 effective to permit rotation and sliding movement on its side-bar and also having opposite thereto a radial slot, said sleeve also having a laterally extending hood adjacent to said radial slot, and a bolt carried by said side-bar and coöperating with said slots whereby the leg may be rotated and slid to lock the same against movement.

7. In a structure of the class described having side-bars, legs provided with sleeves

mounted for rotation upon said bars, each of said sleeves having a radial slot, and a laterally projecting hood, and a clamping bolt carried by said bar and projecting

5 through said slot.

8. In a structure of the class described having side-bars, legs provided with sleeves mounted for rotation upon said bars, each of said sleeves having a pair of differently

10 formed slots at opposite points and a later-

ally projecting hood adjacent to one of said slots, and clamping bolts carried by said bar, one coöperating with each pair of said slots.

Signed at 1821 Park Row Bldg., New 15 York, N. Y., this 16th day of April, 1912.
